UNITED STATES PATENT OFFICE.

AUGUSTIN HENDRICKS, OF GRAND RAPIDS, MICHIGAN.

CASTER ATTACHMENT FOR ADDING-MACHINE STANDS.

No. 823,468.

Specification of Letters Patent.

Patented June 12, 1906

Application filed August 22, 1904. Serial No. 221,701.

To all whom it may concern:

Be it known that I, AUGUSTIN HENDRICKS, a citizen of the United States, residing at Grand Rapids, in the county of Kent and State of Michigan, have invented certain new and useful Improvements in Caster Attachments for Adding-Machine Stands; and I do hereby declare the following to be a full, clear, and exact description of the invention, such as will enable others skilled in the art to which it appertains to make and use the same.

My invention relates to improvements in stands for adding-machines; and its object is to provide the same with means whereby they may be readily moved from place to place and when in use may be securely held from moving and to provide the device with various new and useful features, hereinafter more fully described and particularly pointed out in the claims.

My device consists, essentially, of a stand adapted to adjustably support the machine and mounted on a tripod having one leg bifurcated or divided and spaced apart at the lower end, substantially as shown in the drawings and hereinafter described, reference being had to the accompanying drawings; in which—

Figure 1 is a front elevation of a device embodying my invention, and Fig. 2 an enlarged detail in vertical section on the line 2 of Fig. 1.

Like numerals refer to like parts in both of the figures.

1 represents an adding-machine as usually constructed and provided with an operating-lever 2 at one side. This machine constitutes no part of my invention and is shown merely to illustrate the use of my device in supporting the same.

3 is a suitable spider, preferably of cast-iron, having a central hub adapted to be attached to the screw 5 and radial arms 3 projecting a suitable distance to extend beneath the respective corners of the machine and provided with suitable sockets 4 to receive the legs of the machine. This spider is attached to the upper end of the vertically-adjustable screw 5, inserted in the tubular stand-

ard 6, which standard is supported upon a tripod consisting of the diverging legs 12, all of which legs are mounted on casters 17 for moving the device freely from place to place. To prevent the stands from moving when the machine is in use, the front leg 12 is divided or bifurcated near its lower end and spaced apart, as at 15, whereby two points of contact with the floor and at a distance apart are provided, and thus the stand is prevented from moving when the lever 2 of the machine is operated, whereas if the machine were standing upon casters throughout or upon two casters and one leg it would be likely to move. This divided leg is also provided with a vertical tubular socket 13, in which is inserted a vertically-movable caster-pintle 16 rotative therein; on the lower end of which pintle is a caster-wheel 17, which when depressed engages the floor and raises the members 15 clear of the same, and thus carries the leg upon the caster-wheel 17. To depress this pintle, a cam 14 is pivoted in the upper part of the socket 13 and engages the end of the pintle 16. When this cam is turned with its full side downward, it depresses the pintle. This cam is provided with a suitable depression 19, which prevents the cam from being displaced and furnishes a socket in which the end of the pintle is rotative. To prevent the pintle from dropping out, it is reduced in diameter, as at 20, and a screw 18 is inserted in the socket 13 and extends opposite this reduced portion, and thus limits the downward movement of the pintle.

It is obvious that the device is also adapted to support a type-writing machine or any other light machine of analogous character. It can also be readily adapted to various styles and sizes of machines by providing suitable spiders of various proportions to be used in place of the one herein shown, as occasion may require.

Having thus fully described my invention, what I claim, and desire to secure by Letters Patent, is—

1. In a stand for adding-machines or the like, a tripod having two legs mounted on ordinary casters and a third leg bifurcated or

divided and adapted to engage the floor at two remote points and mounted on a vertically-adjustable caster.

2. In a stand for adding-machines, or the like, a tripod having two legs mounted on casters, each caster being rotative about a vertical axis, and the third leg divided or bifurcated and spaced apart to contact the floor at two remote points, and mounted on

a vertically-adjustable caster located between the ends of said leg and rotative about a vertical axis.

In testimony whereof I affix my signature in presence of two witnesses.

AUGUSTIN HENDRICKS.
